UNITED STATES PATENT OFFICE.

JOHN W. HUDSON, OF BROOKLYN, NEW YORK.

INTERNAL-COMBUSTION ENGINE.

1,400,485.

Specification of Letters Patent. Patented Dec. 13, 1921.

Application filed September 3, 1919. Serial No. 321,380.

To all whom it may concern:

Be it known that I, JOHN W. HUDSON, a citizen of the United States, residing at Brooklyn, in the county of Kings and State 5 of New York, have invented new and useful Improvements in Internal-Combustion Engines, of which the following is a specification.

This invention relates to internal combustion engines generally.

An object of the invention is to provide an improved method of vaporizing the fuel and for delivering the same to the cylinders so that the engine will develop maximum 15 power with a minimum of fuel. Manifestly no power is obtained from fuel which is not burned. The gasoline must be completely vaporized and properly mixed to create full efficiency and prevent carbon deposits, the 20 latter caused usually by poorly burned fuel or an over supply thereof. It is fully recognized that complete vaporization is attained and maintained by spraying the fuel and breaking it up so that a large surface is exposed to the air and by heating either the 25 air or fuel before delivering it to the cylinders. To my knowledge, no means have been employed for sufficiently heating the fuel and for simultaneously disintegrating it so 30 that when it enters the cylinders it will be fully vaporized and retained in this state against possible condensation until an actual explosion thereof is required. Ordinarily, a carburetor becomes cold due to vaporization 35 of the vapor and it obviously follows that instead of the cylinders being supplied with properly vaporized fuel, the fuel enters the cylinders in drops or in a condensed state. This occurs also through the cooling 40 of the intake manifold or by other causes and what for one or the other, it is extremely difficult to obtain such working results which give to the engine its full measure of efficiency.

45 The functioning of a suitable carburetor is fully appreciated and in carrying my invention into practice, I make use of a novel form of carburetor which, from practical experience, is necessary to a correct working 50 of my vaporizer and I have designed and combined these two structures so that besides an initial breaking up of the fuel after it leaves its source of supply, it is subjected to the action of heat at the proper point and

then delivered to a final vaporizing treatment where it is rendered dry and vaporized before admitted to the cylinder.

It is further appreciated that the vaporizing of fuel is only partly essential to a proper working of an internal combustion engine and that air in properly measured quantities must be provided before the fuel is suitable for delivery to the cylinders. If more than the proper amount of air is mixed with the fuel, the mixture will be too lean 65 and many troubles will follow such as back fire through the carburetor and missing of the engine. If too small a quantity of air is admitted, the mixture is too rich and will not burn completely which results in carbonized cylinders, over heating thereof and a general loss in efficiency.

It is therefore a further object of the invention to provide a form of carburetor which will be accurate in its operation after 75 its initial adjustment to admit properly measured quantities of air in proportion to the heated condition of the fuel and the measure thereof, giving a correct measure of air and fuel, weight for weight at all times 80 regardless of the speed which the engine attains. In this connection, I wish also to emphasize the design and construction of an engine in which the above stated instrumentalities will be incorporated so that when 85 the engine is used in connection with aeroplanes, the carburetor may be accurately adjusted through a correcting shutter so as to regulate the admission of air as the altitude of the aeroplane changes, it being 90 understood that the higher the altitude, the greater the amount of air necessary to the creation of a combustible mixture.

Another object of the invention lies in the provision of an engine whereby fuel and 95 air may be initially taken in while in a cold state and then heated and then atomized and finally delivered to the cylinders in a thoroughly vaporized condition.

Another object of the invention is to provide an engine of the radial cylinder type wherein a crank case is incorporated and utilized as a heating surface for the air and fuel after it leaves the carburetor; further incorporating in the engine a carburetor 100 which will exclude the known float and well principle for admitting fuel to the engine so as to avoid consequent carrying in of fuel 105

in drops; providing a form of carburetor which will act to initially break up the fuel before it is delivered to the crank case, and further the provision of a structure which 5 will include a chamber having a filling of suitable material against which the admitted mixture will impinge and flow and through the action of suction whereby when it reaches the cylinder it will be in a perfect vaporized 10 condition.

The invention consists of the parts as hereinafter more fully described and claimed, having reference to the accompanying drawings, in which:—

15 Figure 1 is a section through the engine with parts in full lines.

Fig. 2 is a vertical section through the carburetor, and

20 Fig. 3 is a bottom plan view of the carburetor.

In carrying the invention into practice, I have shown a motor or power plant in which cylinders radiate from a fixed crank case. Following the design shown herein 25 radial cylinders are employed but I of course do not wish to limit myself to this precise arrangement nor do I wish to limit myself to the provision of a fixed crank case inasmuch as it may be desired in some instances 30 to mount the same and the cylinders to revolve.

The power plant comprises a casing 5 with which radial cylinders 6 are incorporated. In the cylinders are reciprocating pistons 7, 35 whose rods 8 are connected in any suitable well known manner with the pins 9 of a crank shaft 10. The crank shaft extends through the crank case 11 and it is separated therefrom by suitable anti-friction bearings 12 40 which may also be of any suitable well known design and construction. Each cylinder is provided in its outer head with inlet and exhaust valves 13 and 14 respectively whose controlling mechanism 15 is 45 actuated by power transmitting rods 16 which, in turn, are controlled by cams 17 and 18 mounted upon the crank case as clearly illustrated in Fig. 1. This construction may also be of any suitable well 50 known and approved design and any departure may be made therein which may be most suitable for a proper functioning of my invention.

Leading into the casing 5 at one side of the engine is an intake pipe 19 whose end 55 20 is equipped with a carburetor 21, said end 20 being flanged at 22 and having connected therewith suitable brackets 23 in which pipe like sections 24 and 25 are mounted and 60 arranged so that one of said sections constitutes the intake for fuel. The inner ends of the pipe like sections are integral with a cruciform connector 26, the branch 27 of which constitutes a stand pipe, the latter 65 entering the end 20 of the pipe 19 and at one

end it is provided with an internal valve seat 29 with which a flared valve 30 co-acts so as to regulate the introduction of fuel to the intake pipe 19. The walls of the valve 30 are curved outward and then angularly at 31 to constitute a baffle or annular apron for a purpose to be hereinafter explained. The outwardly extending portion of the valve is provided with an annular series of perforations 32 which act to disintegrate the fluid as air is drawn into the pipe 19 so as to atomize the fluid and cause a good mixture of same with the air before the mixture proceeds to the crank case of the engine. 75

Surrounding the branch 27 and spaced therefrom is a shell 33 which constitutes a choke or Venturi tube, the same preferably formed as an integral part of a flange 34 which is secured to the flange 22 at the inlet end 20 of the pipe 19, the said flange 34 having radially spaced arms 35 so that radial air spaces 36 are formed therebetween which communicate with the space between the walls of the pipe 19 and the outer walls of the choke or Venturi tube 33. This construction is provided so that air entering the pipe 19 between the inner walls thereof and the outer walls of the choke or Venturi tube 33 will cause suction to be induced at 95 the point 36 around the valve 30, causing the air and fuel to thoroughly intermingle and to be disturbed to insure the formation of a good mixture before the fuel enters the crank case. The induced suction as described above is produced by action of the pistons 7. 100

Movably mounted under the flange 34 is an air valve or shutter 37 which is connected with a controlling stem 38 of the valve 30 by an actuating device 39 whereby when the valve stem is adjusted the valve or shutter 37 will be also moved so as to uncover the end 20 of the pipe 19 and permit properly proportioned quantities of air and fuel to enter the pipe 19 for subsequent delivery to the crank case. 110

The engine is designed primarily for use in connection with airoplanes or flying machines and in order to permit the engine to 115 operatively adapt itself to high and low altitudes, I provide in addition to the valve or shutter 37, a similar co-acting valve or shutter 40, the same arranged under the plate 34 where it will respectively cover and 120 uncover part of the intake 20 of the pipe 19. The last named valve or shutter is adapted to be manually controlled and it is provided with an operating device 41 for such purpose. Under ordinary atmospheric 125 conditions, the first mentioned valve plate or shutter is used in conjunction with the fuel valve 30 but in high altitudes, the second or correcting valve can be immediately thrown into operation so as to give to the 130

5 mixture a larger volume of air and thereby insure a perfect working of the engine. When the said air valves are opened it will be appreciated that in addition to the air 10 entering the space between the inner walls of the pipe 19, and the outer walls of the choke or Venturi tube 33 it will first enter the space surrounding the fuel stand pipe 27 where it will be drawn toward the apron 31 15 to cause the fuel to be atomized by its passage through the perforations 32.

From the foregoing it will be seen that fuel and air are taken at a low temperature and conveyed to the crank case of the engine 20 where its temperature will be raised by the heat from the engine. In order to effect a 25 perfect vaporization of the fuel I provide the engine casing 5 with a rectifying chamber 42 which opens to the crank case at the opposite side of the engine by way of 30 passages 43. A disintegrator 44 is mounted to entirely fill said chamber, the same consisting preferably of closely nested aluminum wire coils 45 which are arranged to be heated 35 by conduction and radiation so that when suction is induced in the chamber the fuel and air will be drawn from the crank case and made to impinge against the surface of the coils 45 to be broken up and further 40 atomized and fully vaporized. While I have described that the disintegrator is constructed of aluminum wire coils, I do not wish to be limited in this respect as any suitable well-known structure may be substituted 45 therefor, such as wire gauze or the like. The intake manifold 46 which leads to the intake valves of the respective cylinders of the engine is also connected by a lead 47 so that when the said valves are opened in the ordinary 50 working of the engine, suction will be induced in the chamber 42 and the combustible products in a properly atomized and heated condition delivered directly to the cylinders.

55 In view of the particular design of engine which I propose to use in connection with flying machines, it will be observed that the construction of the carburetor is such that regardless of the angle or position assumed by the machine while in flight, the 60 flow of fuel (per requisite measure) through the valve will remain consistently the same. The possibility of undue flooding of the carburetor as experienced with the float type of 65 carburetor is entirely eliminated. It will be seen that the stand pipe 27 may be supplied with any desired quantity of fuel by means of the needle valve 25^a and it is preferred that the latter be controlled so that 70 said pipe is not full of fuel at all times. The niceties of construction also prevent improper feeding of fuel to the engine in cold weather, it being understood that should the atomizing openings become clogged or should 75 the vapor around or in the openings freeze,

the fuel will still find adequate escape by way of the space between the valve seat and the flared face of the valve.

The adjusting device 39 for the shutter 37 preferably consists of threaded sections 39^a 70 and 39^b, adjustably connected together by a nut 39^c whereby the several parts when taken together constitute a turn buckle which will permit of adjustments of the shutter to varying degrees according to the admission of 75 air desired. The said threaded sections 39^a and 39^b, are retained in their adjusted positions through the provision of jam nuts 39^d, on said sections, the same adapted to be advanced against the ends of the mentioned 80 nut 39^c.

The connection 25 carries a needle valve 25^a which may be manually actuated to control the flow of fuel to the valve 30, and from the relative positions of these valves, it will 85 be appreciated that suction induced at the valve 30 will draw the fuel from the valve 25^a in spray form so as to further increase the efficiency of the carburetor.

The rectifying chamber 42 is designed 90 and proportioned so that when fluid is introduced thereto through a pet cock 42^a, a reservoir is formed from which gas can be immediately drawn and the engine started.

From the construction of the carburetor, 95 it is observed that fuel is taken into the crank case in a semi-liquid form and preliminarily heated by contact with heat in the crank case. The chilled condition of the fuel as it enters the crank case serves to cool the 100 heads of the pistons which adds materially to the general efficiency of the motor, while permitting the fuel to be pre-heated before it reaches the rectifying chamber 42.

What is claimed as new is:—

1. The combination with an internal combustion engine, including a crank case and crank shaft, the former having radial cylinders provided with reciprocating pistons, operatively connected with the crank shaft, a 110 rectifying chamber embracing the crank shaft, means for delivering fuel to the chamber, means in the chamber for rectifying the fuel by impingement of the fuel against said means to disintegrate the fuel, and means 115 between the cylinders and the chamber for conducting the fuel to the intake valves of the cylinders.

2. The combination with an internal combustion engine including a crank case and 120 crank shaft, the former having radial cylinders provided with reciprocating pistons, operatively connected with the crank shaft, a rectifying chamber embracing the crank shaft, means for delivering fuel to the chamber, means in the chamber for rectifying the fuel by impingement of the fuel with said means so as to disintegrate the fuel, and means between the cylinders and the chamber 125 for conducting the rectifying fuel to the 130

intake valves of the cylinders, said crank case supporting the cylinders, and arranged in direct communication with the chamber.

3. The combination with an internal combustion engine including a crank shaft, a cylinder having a reciprocating piston working therein and connected with the crank shaft, inlet and exhaust valves carried by the cylinder, of a rectifying chamber, means for feeding fuel to the chamber, and a disintegrating member mounted in the chamber and including closely nested windings against which the fuel is adapted to impinge during the rectifying process, the chamber having operative connection with the inlet valve of the cylinder and opening to the crank case directly at one side thereof.

4. In an internal combustion engine, the combination of a crank case, cylinders radiating therefrom, pistons working in said cylinders, intake and exhaust valves respectively for the cylinders, a rectifying chamber opening to the crank case at one side of the engine, a carbureter opening to the crank case at the opposite side of the engine, said carbureter including a valve for the admission of fuel, a valve for the admission of air, a controlling device for the fuel and air valves, a correcting valve co-acting with the air valve to regulate the admission of air above the normal admission as caused by said air valve, and means for regulating said correcting valve.

5. The combination with an internal combustion engine including a crank case, an intake manifold, and a rectifying chamber leading to the manifold, of a carbureter opening to the crank case and including a pipe for the admission of air and fuel at a low temperature to the crank case, a Venturi tube extending into the pipe, a valve co-acting with the tube, a fuel supplying connection leading to the tube, an air valve working over one end of the pipe, and means for operating both valves simultaneously.

6. The combination with an internal combustion engine including a crank case, an intake manifold, and an atomizer leading to the manifold, of a carbureter opening to the crank case and including a pipe for the admission of air and fuel at a low temperature to the crank case, a Venturi tube extending into the pipe, a valve co-acting with the tube, a fuel supplying connection leading to the tube, an air valve working over one end of the pipe, means for operating both valves simultaneously, a correcting valve co-acting with the air valve for enlarging the admission of air to said pipe, and means for controlling the correcting valve.

7. The combination with an internal combustion engine including a crank case, of a carbureter opening to the crank case at one side of the engine, a pipe leading to the crank case from the opposite side of the engine, independently movable valves operating over one end of the pipe, devices for moving said valves, a tube opening into the pipe and passing between the valves, a valve for said tube, the moving device of one of the first valves serving to control adjustments of the last named valve, a fuel connection leading to the tube, and a shell embracing the tube and spaced therefrom, said shell rising above the valve end of the tube and having its opposite end exposed to the independently movable valves so that fuel will be discharged from the tube in an atomized state by induced suction within the area of the shell and sprayed laterally throughout the transverse area of the pipe prior to an admission of the mixture to the crank case.

8. The combination with an internal combustion engine including a crank case, cylinders having intake and exhaust valves respectively, a manifold leading to the intake valves and a rectifying chamber between the crank case and manifold of a carbureter including a fuel stand pipe, a Venturi tube surrounding the fuel stand pipe, an intake pipe constituting part of the carbureter and leading to the crank case at the opposite side from the atomizer, a valve for the fuel stand pipe, a valve operating over the carbureter pipe which leads to the crank case, means for successively uncovering the Venturi tube and the space between it and the carbureter pipe which leads to the crank case, and a fuel supply connection leading to the fuel stand pipe.

9. The combination with an internal combustion engine, of a carbureter connected with the crank case thereof, a rectifying chamber connected with the crank case and opening thereto, a fuel delivery connection between said chamber and the cylinders of the engine so that under the action of induced suction, fuel will be drawn from the carbureter; through the crank case, thence to the rectifying chamber, and from the latter to the cylinders of the engine, and a coil located in said chamber, the fuel on entering the chamber serving to come in direct contact with the outer surfaces of the windings of said coil so as to disintegrate the fuel before passage thereof to the delivery source.

In testimony whereof I have affixed my signature.

JOHN W. HUDSON.
